ALONZO L. GIBBS, OF WAGONER, OKLAHOMA, ASSIGNOR OF ONE-HALF TO O. W. MUNCH, OF WAGONER, OKLAHOMA.

REFRIGERATING-MACHINE.

1,345,001.

Specification of Letters Patent. Patented June 29, 1920.

Application filed March 9, 1918. Serial No. 221,460.

To all whom it may concern:

Be it known that I, ALONZO L. GIBBS, a citizen of the United States, residing at Wagoner, in the county of Wagoner and State of Oklahoma, have invented certain new and useful Improvements in Refrigerating-Machines, of which the following is a specification.

This invention has relation to the art of refrigeration, and has for an object to provide a refrigerating system designed particularly for use in small refrigerators, and to that end comprises a minimum number of parts of an inexpensive character permitting the economical construction and maintenance of the system.

Another object of the invention is to provide a refrigerating system embodying the direct expansion principle and including a pair of generators for generating ammonia gas, one generator adapted to contain a rich liquor and the other a weak liquor with condenser and other appurtenant parts of the refrigerating system connected thereto whereby the gas may be driven from the generator containing the rich liquor and subsequently absorbed after expansion in the generator containing the weaker liquor.

Another object of the invention is to provide a refrigerating system embodying a pair of generators of the character above set forth and means whereby either generator alternately or simultaneously may be heated for the purpose above set forth.

A still further object of the invention is to provide a refrigerating system of the direct expansion type embodying a generator, rectifier, condenser, separator, and expansion coils, connected in a manner to permit a cyclic or continuous operation of the system, and a cooling system extending through the various elements thereof and operable to progressively cool the elements during the flow of fluid from one end of the system to the other.

In addition to the foregoing my invention comprehends improvements in the details of construction and arrangement of the parts to be hereinafter more fully described and particularly set forth in the appended claim.

In the accompanying drawings in which similar and corresponding parts are designated by the same characters of reference

throughout the several views in which they appear:

Figure 1, is a diagrammatic view illustrating the various elements of my improved refrigerating system and their association, and

Fig. 2, is a diagrammatic view illustrating the connection to the heating coil.

The various elements of the generating, condensing and expansion elements of the system will be considered first and subsequently the method of cooling the same. Therefore, with reference to the drawings, 10 and 11 indicate a pair of generators in the form of tanks, which may be disposed vertically in small systems and horizontally in larger systems. A heater is located between the generators and consists of a furnace 12 having a vertical coil 13 located therein. The upper end of the coil is connected to pipes 14 and 15 which lead to the upper ends of the tanks 10 and 11 respectively while the lower end of the coil 13 is connected to pipes 16 and 17 which lead to the lower ends of the tanks 10 and 11 respectively. The pipes 16 and 17 have valves 18 and 19 interposed therein. The lower ends of the generators 10 and 11 are connected by means of a pipe 20 which is formed with an upper bend having valves 21 and 22 located therein adjacent the points of connection of said connecting pipe with the generators 10 and 11 respectively, drain cocks 23 being also located in said pipe adjacent the lowest point of the upward bend.

The tanks 10 and 11 are also connected at vertically spaced points by means of horizontal pipe connections 24 and 25. Said pipe connections 24 and 25 are then connected at points intermediate their ends by means of a gage 26 of conventional type to indicate the height of the fluid within the generating tanks, controlling valves 27 being located in the pipe connections, two in each connection, one at each side of the gage 26 whereby superposed valves at one side of the gage may be closed and the other superposed valves opened to indicate the height of the fluid in one generating tank or the other as the case may be. Vertical pipe sections 28 and 29 are connected to the upper ends of the tanks 11 and 12 respectively, and continuations of said pipe connections are extended horizontally in opposite directions

100
105

as indicated at 30 and 31 respectively. The terminals of said horizontal portions 30 and 31 are then connected together by means of a horizontal pipe section 32 having valves 33 and 34 located in its ends to control the generators 10 and 11 respectively. A T-coupling 35 is located in the pipe connection 32 at a point intermediate its ends and to one branch of the T-coupling there is connected a pipe connection 36 leading to a rectifier 37 consisting of a vertical coil of piping, the pipe connection leading to the upper end thereof. To the lower end of the coil 37 there is connected a pipe connection 38 leading to a separator 39 consisting of a vertically disposed tank, the connection 38 entering the same at a point intermediate its ends. A pipe connection 40 is established at the upper end of the separator 39 and leads into the upper end of a condenser coil 41. A hand or expansion valve 42 is interposed in said connection 40 as is also a purge valve 43. The lower end of the vertical condenser coil 41 extends into a tank 44 to collect anhydrous ammonia, and a valve 45 is located in the coil 41 at a point adjacent its point of entrance into the tank 44. A pipe connection 46 is established at the lower end of the tank 44 and leads upward and into an expansion coil 47 which may be located in a refrigerator or any other compartment to be cooled. An expansion valve 48 is located in said pipe connection before its connection to the coil 47, and a valve 49 is also located in the pipe connection at a point adjacent the point of connection to the tank 44. The opposite end of the cooling coil is then extended downwardly as at 50 and provided with a T-coupling 51 at a point intermediate whereby a pipe connection 52 may be established between said T-coupling and the lower end of the separator 39. A valve 53 is interposed in connection 52 as shown. The extreme lower end of the pipe section 50 is then connected to a T-coupling 54 which is interposed in the above mentioned pipe connection 20 which connects the lower ends of the generators 10 and 11.

The elements of the refrigerating or expansion system proper having been described, the elements of the cooling system will next be considered. A pipe 55 extending from a source of cool water is led into the lower end of the anhydrous ammonia tank 44 without connection to the interior thereof and is connected to one end of a tube 56 which extends throughout the length of and surrounds the condenser coil 41 in spaced relation to the outer sides thereof and effects an exit at the upper end of the condenser coil through the provision of a welded section 57 and is connected to a pipe section 58 which leads to a tubular section 59 which extends throughout the length of the coil of the rectifier 37 in spaced relation to

the inner sides thereof and effects an exit at its upper end and is connected to a pipe connection 60. This pipe connection leads downward and is connected to a sleeve 61 which surrounds the horizontal portion 30 of the pipe connection of the generator tank 11, said sleeve being in spaced relation to said horizontal pipe section to define an annular chamber. One end of the sleeve 61 is connected by means of a connection 62 to a similar sleeve 63 surrounding the horizontal portion 31 of the pipe connection to the generator tank 11. The opposite end of the sleeve 63 is then connected by means of a short pipe connection 64 to a horizontal pipe connection 65 located above and extending between the generator tanks 10 and 11. A T-coupling 66 is located at a point intermediate the ends of the pipe section 66 for connection to a pipe 67 which conducts away the water to a sewer. The ends of the pipe connection 65 are then extended into the generator tanks 10 and 11 and connected to coils 68 which are located therein and are extended throughout the length thereof, the lower ends of the coils effecting an exit through the lower ends of the tanks 10 and 11 and are provided with valves 69, controlling communication between said coils and pipe connections 70. The pipe connection 65 is also provided with valves 71 at points adjacent the point of connection of said pipe connection 65 with the coil 68.

In use, one of the generator tanks, for instance the tank 10 is charged with a suitable quantity of rich aqueous ammonia of amount 30% strength, while the other tank 11 is charged with a similar quantity or more of weak aqueous ammonia of about 5% strength. The coil 13 within the furnace is then heated by gas, charcoal or other suitable fuel, and the valve 19 closed, and the valve 18 opened. The aqueous ammonia in the tank 10 is then permitted to circulate through the heating coil and the gaseous ammonia is quickly driven off. Prior to the charging of the system however, it is necessary that the entire system be exhausted of air to the highest degree of vacuum practicable. If the ammonia in the tank 10 is heated, the valves 33 must be open, the valve 53 closed, and the valve 42 open. The heating of the aqueous ammonia is continued until the pressure within the system rises to approximately 100 lbs. per square inch, and the valve 54 controlling the supply of water to the coil 56 is open, permitting the cooling fluid to flow through said coils 56, the pipe connection 58, the coil 59 of the rectifier 37, the pipe connection 60, sleeves 61 and 63, passing through the connections 64 and 65, effecting an exit through the connection 67. The valve 71 should be closed so as to prevent the passage of water through the coil 68 of the generator 130

tank 10. The other valve 71 however may be open to permit the fluid to pass through the coil 68 of the generator tank 11 inasmuch as it is essential that the weak liquor be retained at a low temperature. The gaseous ammonia passing from the generator 10 through the pipe connections 28, 30, 32, and 36 to the rectifier 37 is subjected to a preliminary cooling in said rectifier and is then passed into the separator 39 where water of condensation is collected. The gaseous ammonia is then conducted into the condenser 41 and owing to the combined action of the cooling fluid and the pressure in the system induced by the heat of the generator tank 10, the gaseous ammonia is liquefied and collected at the bottom of the tank 44. The liquefied or anhydrous ammonia is then permitted to enter through the expansion valve 48 into the expansion coil 47 which is of a relatively large diameter whereby the rapid evaporation of the anhydrous ammonia results in the depression of the temperature of the coil and the air surrounding the same so as to cool the interior of the refrigerator or other cooling compartment. The gaseous ammonia, after evaporation thus superinduced, is conducted through the returns 50 into the pipe connection 20 and owing to the fact that the valve 21 is closed, and the valve 22 is open, the gas is permitted to enter the weak liquor in the tank 11 and is quickly absorbed. This process continues until the strength of the liquor in generator 10 is reduced to 5% and the strength of the liquor in tank 11 increased to approximately 30% when the valve 18 is closed and the valve 19 opened so that liquor in the tank 11 may be heated. Other valve adjustments which are obvious must yet be made to properly conduct the cooling fluid and the process of generation will continue in the tank 11 in the same manner as that just described.

Thus it will be seen that I have provided a refrigerating process which is cyclic or continuous in its action in that the absorption of gas takes place automatically without requiring the interchange of liquors of various strengths after the system has once been charged. Other uses and advantages of this system will readily occur to those fa-

miliar with the art to which this invention appertains. In small plants for domestic use the coils in the generator tanks and in 55 the anhydrous ammonia tank 44 will be eliminated.

While I have illustrated and described my invention with some degree of particularity, I realize that in practice various alterations 60 thereover may be made, and I therefore desire to reserve the right and privilege of changing the form of the details of construction or otherwise altering the arrangement of the correlative parts without departing from the spirit of the invention or the scope of the appended claim.

Having thus described my invention what I claim as new and desire to secure by Letters Patent is:—

In a refrigerating system, a pair of generating tanks having their lower ends provided with a connecting pipe connecting the interiors of the tanks, a heating coil, connections between the upper end of the coil 75 and the upper ends of the said tank, horizontally disposed pipes arranged above the tank and each having one end communicating with one of the said tanks, a condenser coil, and an expansion coil, a pipe connecting 80 the said expansion coil with the said connecting pipe for the said tanks, a separator having connection with the said last mentioned pipe and connected with the said condenser coil, a supply pipe connected to a 85 source of cool water supply, a tube connecting with the said supply pipe and surrounding the said condenser coil, and having one end at the top of the condenser coil equipped with a pipe extension leading from 90 the said tube, a rectifier, the said pipe from the upper end of the tube extending through the length of the coil of the said rectifier in spaced relation to the inner sides thereof, and sleeves surrounding the said 95 horizontally disposed pipes and connected to the said tube surrounding the said rectifier coil.

In testimony whereof I affix my signature in presence of two witnesses.

ALONZO L. GIBBS.
